UNITED STATES PATENT OFFICE.

GEORGE WHITMAN MERRILL, OF TULSA, OKLAHOMA.

MEANS FOR SEALING STORAGE-TANKS.

1,266,843.

Specification of Letters Patent. Patented May 21, 1918.

Application filed March 24, 1917. Serial No. 157,132.

To all whom it may concern:

Be it known that I, GEORGE W. MERRILL, a citizen of the United States, and a resident of Tulsa, in the county of Tulsa and State 5 of Oklahoma, have invented certain new and useful Improvements in Means for Sealing Storage-Tanks, of which the following is a specification.

My invention relates to improvements in 10 means for sealing storage tanks, and it consists in the combinations, constructions and arrangements herein described and claimed.

An object of my invention is to provide a storage tank for volatile oils having means 15 for sealing the joint between the body portion of the tank and the roof, so as to prevent the escape of the gas.

A further object of my invention is to provide means for sealing the joints between 20 the roof and sides of a storage tank and at the same time providing means for conducting charges of electricity from the roof to the sides of the tank or vice versa.

A further object of my invention is to 25 provide a sealing means of the type mentioned, which is applicable to metal tanks of existing types, and in which the conducting means between the roof and sides of the tank also serve as retaining means for the 30 sealing compound.

Other objects and advantages will appear in the following specification, and the novel features of the invention will be particularly pointed out in the appended claims.

My invention is illustrated in the accompanying drawings which form a part of this 35 application, and in which:

Figure 1 is a perspective view of one form of the invention.

Fig. 2 is a detail sectional view through the sealing means of the tank shown in Fig. 1.

Fig. 3 is a view of a modified form of the invention, and

Fig. 4 is a sectional view through the sealing means shown in Fig. 3.

In carrying out my invention I make use of any of the ordinary metal tanks which are designed to hold volatile oils such as 50 gasoline, benzine, kerosene and the like. Ordinarily the joints between the roof and the sides of these tanks are not gastight, so that considerable leakage of gas results. Furthermore, the escape of the highly inflammable gas renders the tank very liable 55 to take fire because of the fact that during

electrical storms these tanks become charged with static electricity. Sparks produced by the discharge of this static electricity are very apt to ignite the escaping gas and thereby set fire to the tank.

Referring now to Fig. 1 I have shown therein a storage tank having metal sides 1 and a metal roof 2. For the operation of sealing the roof of the tank, the metal covering of the roof is first removed and all joints and warped places are repaired. The metal covering is then replaced to conform with the wooden sheathing, galvanized nails being used to hold the covering in position. In 65 all joints, nail holes and other openings, and also around gage holes and pipe lines, a fire resisting cement is placed.

For the sealing of the joint between the side walls and the roof we use a specially 75 prepared sealing compound which makes a permanent gas-tight joint. While the composition of this sealing compound may be varied, we prefer to use a sealing compound prepared from elastic, adhesive, water-proof 80 gums with which is incorporated a long fiber asbestos. This has great elasticity and resiliency and withstands heat and moisture.

In order to hold the sealing compound in 85 position a backing 3, of L shaped cross section is provided, the lower part of this backing resting upon metal brackets 4. The sealing compound 5 is filled in between the bracket 4 and the projecting edge of the roof in the manner shown in Figs. 2 and 4. This 90 sealing compound is a poor conductor of electricity. In order to hold the sealing compound in position and at the same time to furnish a conducting medium between the bracket 4 and the roof 2, I provide an arrangement like that shown in Figs. 1 and 2, in which wires 6 are laced back and forth through openings in the edge of the roof 2 and openings in the bracket 4. These wires 95 form ample means for conducting a charge of electricity to the roof from the sides of the tank or vice versa and at the same time they tend to keep the sealing compound in position.

In Figs. 3 and 4 I have shown a modified 105 form of the device in which instead of using wire lacing, the retaining and conducting means consists of wire netting, 6*. One edge of this netting is attached to the roof and the other to the bracket 4*. Both the lacing 110 6 and the netting 6*, extend entirely around the edge of the roof where it joins the side

walls, thus holding the sealing compound in position.

I claim:

1. The combination with a metal storage tank having side walls, of a backing of L-shaped cross section disposed exteriorly of the tank walls near the top thereof, auxiliary means for supporting said backing, a roof extending beyond the edge of said backing, a plastic sealing compound of substantially triangular shape in cross section, disposed in the angle of said L-shaped backing and having a portion contacting with the under side of the roof and another portion contacting with the backing supporting means.
2. The combination with a metal storage tank having side walls, of a backing of L-shaped cross section disposed exteriorly of the tank walls near the top thereof, auxiliary means for supporting said backing, a roof extending beyond the edge of said backing, a plastic sealing compound of substantially triangular shape in cross section, disposed in the angle of said L-shaped backing and having a portion contacting with the under side of the roof and another portion contacting with the backing supporting means, and conducting members extending from said backing supporting member to the roof for holding said backing material

in place and for providing an electrical conductor from the walls to the roof, exteriorly of said plastic compound.

3. The combination with a storage tank 35 having metallic walls, of a backing of L-shaped cross section secured to said walls near the tops thereof, metal brackets at the bottom of said backing for supporting the latter, said brackets being secured below the 40 walls, a roof extending beyond the edge of said L-shaped backing, plastic sealing material disposed in the angle of said L-shaped backing member and extending beyond the outer edge thereof, said plastic material en- 45 gaging the under side of the roof at its upper end and engaging the supporting brackets at its lower end, and a wire netting secured to the end of the roof beyond the junction of the roof with said sealing com- 50 pound at its upper end and being secured to the brackets at its lower end, said netting being arranged to bear on said plastic compound for holding the latter in position and also affording an electrical connection be- 55 tween the walls of the tank and the roof thereof.

GEORGE WHITMAN MERRILL.
